UNITED STATES PATENT OFFICE.

NUNZIO D. CALCULLI, OF NEW YORK, N. Y.

ORTHOPEDIC METATARSAL ARCH-SUPPORT.

1,385,664.

Specification of Letters Patent. Patented July 26, 1921.

Application filed February 17, 1921. Serial No. 445,774.

To all whom it may concern:

Be it known that I, NUNZIO D. CALCULLI, a citizen of the United States, residing at New York city, borough of Manhattan, in 5 the county of New York and State of New York, have invented certain new and useful Improvements in Orthopedic Metatarsal Arch-Supports, of which the following is a specification.

10 This invention relates to orthopedic arch supports and has particular reference to such devices as are adapted not only for supporting the arch but also for the support of the metatarsal portion of the foot and the 15 relief from pressure of any localized soreness in such region.

Among the objects, therefore, of my invention is to provide an arch support of the general nature indicated having peculiarly 20 arranged cushioning and resilient devices for different parts of the sole of the foot as well as providing a suitable support for the arch or instep.

Another object of the invention is to provide a construction most readily adaptable 25 not only for any size or shape of foot but also to give relief or support to any portion of the foot.

With the foregoing and other objects in 30 view the invention consists in the arrangement and combination of parts hereinafter described and claimed, and while the invention is not restricted to the exact details of construction disclosed or suggested herein, 35 still for the purpose of illustrating a practical embodiment thereof reference is had to the accompanying drawings, in which like reference characters designate the same parts in the several views, and in which—

40 Figure 1 is a perspective view of a preferred embodiment of my invention, the cover being omitted.

Fig. 2 is a vertical longitudinal section of the complete device.

45 Fig. 3 is a vertical transverse section on the line 3—3 of Fig. 2 showing especially the shape of the side supports.

Referring now more specifically to the drawings I show my improved arch support 50 as comprising a main body 10 of any suitable tough and slightly flexible material, such as sole leather, cork composition, or the like, shaped to conform to the heel and arch portions of the sole and having inner and outer upturned side supports 11 and 12. The bounding edge of this piece of ma-

terial may be of any suitable shape and preferably is skived down to make it relatively thin for obvious reasons of comfort to the wearer.

60 The central portion of the bottom surface of this body strip 10 is recessed at 13 so as to make it relatively thin along its central portion while the side portions surrounding the recess 13 remain of materially 65 greater thickness and hence stiffness.

The thin portion 14 of the body above the recess is transversely slotted at 15 and 16, and projecting upward through these slits are the end portions of a piece of flat 70 spring material 17, the central or main portion of which lies longitudinally along the recess 13. The spring is so shaped that said end portions tend to be held elevated above the corresponding portions of the body 75 member 10, the rear end of the spring corresponding to the heel portion of the support, while the forward end of the spring projects into the region of the metatarsal joints.

80 A plate 18 of slightly concave form is attached by any suitable means such as a rivet 18' to the heel end of the spring and is thereby held normally elevated from the heel portion of the body. Likewise another 85 plate 19, preferably of convex or spoon shape is attached to the forward end of the spring and so is held elevated thereby. This plate 19 may be attached to the spring by any suitable means, as by soldering and is 90 so arranged or designed as to afford relief from pressure of the foot which would otherwise be received upon any localized sore or weak spots of the metatarsal portion of the foot, to the extent of the strength 95 of the spring supporting the plate 19. That is to say, if a person is suffering from a corn or the like at the ball of the foot in the region of the plate 19, the position of the plate will be so determined as to bear upward on the foot at one side of the afflicted spot, thus affording not only temporary relief but an opportunity for the disturbance to be cured. The spring 17 naturally is 100 held from lateral movement by means of the slits through which it projects, and is held from endwise displacement by any suitable means coöperating with the body 10 such as a rivet 20.

105 The side flanges or wings 11 and 12 are 110 designed and made and shaped to fit the requirements of any individual foot but ex-

tending well upward along the sides of the foot afford unusually good protection for such portions of the wearer's foot.

A body stiffening member 21 is attached 5 to the body 10 by any suitable means such as cement and conforms substantially in outline to the recess 13, the edges of the stiffening member 21 being skived off so as to conform approximately to the shape of the foot 10 or the shape of the shoe intended for such foot.

If desired any suitable form or character 15 of cover 22 may be provided over the entire structure as above described. This cover 20 may be of any suitable soft flexible material such as sheep skin or its equivalent. In my extensive experience in the making of orthopedic sole arch supports during a large number of years I have found that the mechanism disclosed herein is peculiarly well 25 adapted for the purposes set forth and adds greatly to the comfort of the wearer.

It is to be noted that the plates approximate in thickness the thickness of the body 25 of the device above the spring and adjacent to the slits, and hence the upper surfaces of the plates in practice lie substantially flush with that portion of the body above the spring, and said plates may be perforated as 30 shown for ventilation or the like.

I claim:

1. The herein described arch support, comprising a main portion, having a recess formed in its bottom surface, a spring extending longitudinally along said recess and projecting at its ends upward through the upper surface of the main portion and spaced therefrom, and a pair of plates at-

tached to the respective ends of the spring and serving to resiliently support the heel 40 and metatarsal portions of the foot.

2. A device as set forth in claim 1 in which the main portion is transversely slitted, the spring passing upward through the slits and thence rearward and forward over the heel 45 and ball portions of the device at its respective ends, and wherein the thickness of the plates is equal approximately to the thickness of the main portion above the spring.

3. In an arch support, the combination of 50 a stiff arch member, a spring secured thereto and extending longitudinally therewith, the front end of the spring projecting upward from the said member in spaced relation to the ball portion thereof, and a plate attached 55 to said forward end of the spring and thereby held resiliently spaced from the ball portion of the device.

4. A device as set forth in claim 3 in which the plate is of approximately spoon shape. 60

5. A device as set forth herein comprising 65 a rigid arch member having an upper portion having its margin shaped to conform to the shape of the foot, and recessed in its lower surface, a lower portion fitted in said recess, a spring of flat material extending along said recess between the two portions and projecting at its ends upward above the heel and ball portions thereof, a pair of plates attached to said upwardly extending 70 spring ends and so held resiliently spaced normally from the member first mentioned, and a cover of soft pliable material entirely inclosing all of the aforesaid parts.

In testimony whereof I affix my signature. 75
NUNZIO D. CALCULLI.
